UNITED STATES PATENT OFFICE.

CHARLES EVANS BEAN, OF GARNETT, KANSAS.

WASHING-MACHINE.

No. 884,064.

Specification of Letters Patent.

Patented April 7, 1908.

Application filed May 17, 1907. Serial No. 374,233.

To all whom it may concern:

Be it known that I, CHARLES EVANS BEAN, a citizen of the United States, residing at Garnett, in the county of Anderson and State of Kansas, have invented certain new and useful Improvements in Washing-Machines, of which the following is a specification.

My invention relates to improvements in washing machines, and refers in particular to those of the "agitator" type, the object of the invention being the provision of a combined clothes boiler and washer which shall be practical and desirable in every feature.

Another object of the invention is to provide a combined boiler and washer which will subject the clothes to the action of the suds and steam, and to provide improved and simplified mechanism for agitating the clothes and removing the dirt therefrom while being subjected to the cleansing influences of the suds and steam.

With the above and other objects in view, my invention consists of a containing vessel provided with a close fitting cover having a depending flange to provide a steam chamber in the top of the vessel, an agitator depending from the cover and operated by suitable mechanism, and rubbers on the walls and bottom of the vessel.

The invention further consists of a clothes washer embodying certain other novel features of construction, combination and arrangement of parts substantially as disclosed herein and illustrated in the accompanying drawings, in which:

Figure 1, is a sectional side elevation of my improved washing device, parts being broken away to expose the interior thereof. Fig. 2, is a top plan view of the device to more clearly illustrate the operating mechanism.

The device is adapted to be placed upon the stove or other heating medium so as to receive the heat direct therefrom and the clothes receptacle is preferably made of sheet metal in the form of a cylindrical containing vessel 1, which is provided with the usual bails or handles 2, for lifting and carrying the same. A dome shaped cover 3, is provided for the vessel which has a depending annular flange 4, making close engagement with the rim of the vessel to render the cover practically steam tight. A relief cock 5, is preferably mounted on the cover to afford an outlet for the surplus steam. The

cover is clamped down against the rim of the vessel by means of the clamps or catches 6, and it is further provided with the pair of oppositely disposed handles 7. Depending from the inner periphery of the cover, is an additional depending flange 8, which flares inwardly on a curve to provide an annular steam chamber or space around the upper portion of the containing vessel. A bracket 65 plate 9, is secured in a horizontal position on the top of the cover, and journaled in the collar 10, on said plate and passing down through the cover, is the stem 11, which carries on its lower end, the depending, radiating prongs or arms 12, which serve to engage the clothes in the boiler. A driving pinion 13, is mounted on the upper squared end of the stem 11, which is engaged by and meshes with the segmental gear 14, this segmental gear being journaled on the stud or post 15, supported on the bracket plate. A handle 16, is carried by the segmental gear for operating the same.

Arranged on the inner walls of the vessel, 80 are the upwardly tapering substantially cylindrical members 17, which form rubbers for the clothes and being open at both ends, they form conduits for the passage of the steam and water. The lower ends of the 85 tubular rubbers are flanged outwardly as at 18, the flanges being set at a downward incline toward the center of the vessel, and the upper open ends of these vertical passages are preferably set at an incline at 19.

The vessel or tub has a false bottom in the shape of a conical disk 20, which is corrugated to form the radiating ridges 21, and the circumference of the disk is cut away at 22, in order to pass over the vertical rubbers on the 95 walls of the vessel. The edges of the false bottom are supported on the flanges at the base of the tubular rubbers and the central portion of the disk is supported on the depending ring 23, which is secured direct to 100 the disk. The ring is perforated as at 24 to allow for the passage of the water and a stud 25, affixed centrally at the lowermost portion of the disk serves as a handle for lifting and removing the false bottom.

From the foregoing description taken in connection with the drawings, it will be evident that the device serves the double function of clothes boiler and washer in an efficient manner, and that it accomplishes the 110 results herein set forth as the objects of the invention in a highly satisfactory way.

I claim:

1. The combination with a boiler and a tight fitting cover therefor, of tubular open ended rubbers on the walls of the boiler, said 5 rubbers having flanged bases, a perforated false bottom resting on the bottom flanges of the rubbers, an annular inwardly flaring rim depending from the cover forming an annular steam chamber around the head of the 10 boiler, the tubular rubbers opening up into said steam chamber and a clothes agitator depending from the cover below the annular steam chamber.
2. In a washing machine, the combination 15 with a boiler and a tight fitting cover thereto, of tubular open ended rubbers on the interior walls of the boiler having flanged lower ends, a perforated and corrugated conical false

bottom resting on the base flanges of the rubbers, an annular inwardly flaring rim depending from the cover to provide an annular steam chamber in the head of the boiler, said rim being first curved inwardly and then directed downwardly at a slight incline the tubular rubbers having their upper open ends 25 entered in said steam chamber, and a clothes agitator depending from the cover, said agitator having diverging arms projecting below the annular depending rim.

In testimony whereof I affix my signature 30 in presence of two witnesses.

CHARLES EVANS BEAN.
